Patented Mar. 15, 1966

204,122

TURRET LAWN SPRINKLER

Isaac Rinkewich, 290 9th Ave., New York, N.Y.

Filed Dec. 24, 1964, Ser. No. 83,158

Term of patent 14 years

(Cl. D91—1)

FIG. 1

FIG. 2

FIG. 3

FIG. 4

FIG. 5

FIG. 6

FIG. 1 is a perspective view of a turret lawn sprinkler embodying my new design;

FIG. 2 is a top plan view thereof;

FIG. 3 is a side elevational view from one side thereof;

FIG. 4 is a side elevational view from the opposite side thereof;

FIG. 5 is an end elevational view from one end thereof; and

FIG. 6 is an end elevational view from the opposite end thereof.

I claim:

The ornamental design for a turret lawn sprinkler, as shown.
